US00D348900S

United States Patent [19]**Vogel****Patent Number: Des. 348,900****Date of Patent: ** Jul. 19, 1994**

[54] **CORNER CONDUIT FOR A PNEUMATICALLY-PROPELLED CARRIER SYSTEM**

[75] Inventor: **Victor J. Vogel, Oak Ridge, N.J.**

[73] Assignee: **Mosler Inc., Hamilton, Ohio**

[**] Term: **14 Years**

[21] Appl. No.: **948,769**

[22] Filed: **Sep. 14, 1992**

[52] U.S. Cl. **D18/35; 406/191; D23/393**

[58] **Field of Search** .... **406/191, 110-111; 138/DIG. 4, DIG. 11; D18/35; D23/387, 393**

CLAIM

The ornamental design for a corner conduit for a pneumatically propelled carrier system, as shown and described.

DESCRIPTION

FIG. 1 is a perspective view of a 45° embodiment, depicting the top and front of the corner assembly design of this invention;

FIG. 2 is a perspective view, depicting the bottom and rear of the embodiment of FIG. 1;

FIG. 3 is a front elevational view thereof, with the rear elevational view thereof being a mirror image;

FIG. 4 is a left side elevational view thereof;

FIG. 5 is a right side elevational view thereof;

FIG. 6 is a top plan view thereof; and,

FIG. 7 is a bottom plan view thereof.

FIG. 1

FIG. 2

FIG. 4

FIG. 3

FIG. 5

FIG. 6

FIG. 7
